No. 890,250.

PATENTED JUNE 9, 1908.

H. L. THOMPSON.

ANNEALING FURNACE.

APPLICATION FILED MAY 19, 1905. RENEWED NOV. 16, 1907.

UNITED STATES PATENT OFFICE.

HUGH L. THOMPSON, OF WATERBURY, CONNECTICUT.

ANNEALING-FURNACE.

No. 890,250.

Specification of Letters Patent.

Patented June 6, 1903.

Application filed May 19, 1905, Serial No. 261,106. Renewed November 16, 1907. Serial No. 402,531.

To all whom it may concern:

Be it known that I, HUGH L. THOMPSON, a citizen of the United States, residing at Waterbury, in the county of New Haven and State of Connecticut, have invented a new and useful Annealing-Furnace, of which the following is a specification.

My invention relates to annealing furnaces in which the oxidizing atmosphere is excluded from the metal during treatment and until the same has been cooled.

My object is to provide improved means for delivering the metal to the furnace retort without admitting the oxidizing atmosphere thereto, and my invention is especially adapted for continuously operating furnaces.

Referring to the drawings:—Figure 1 is a longitudinal vertical section of the annealing furnace showing my improved mechanism. Fig. 2 is a cross sectional detail of a portion of the charging device.

Similar numerals refer to similar parts throughout the several views.

The retort 1 is of the usual form having a discharging end 2 extending downwardly into the tank 3; its lower end being immersed in the water contained in the tank. In the retort 1 is provided the conveyer 37. At the receiving end of retort 1 is provided the cylindrical casing 4 having at its diametrically opposite side from the retort opening 26, the opening 14. The specific apparatus illustrated is especially adapted for the treatment of stock such for instance as coils of bright metal wire. Within the casing 4 is suitably mounted, on shaft 7, a rotating structure or body having radially disposed partitions 6 secured on both sides to the circular disks 35, thereby forming a series of sector-shaped compartments. The shaft 7 is driven by the chain 8 from pulley 9 mounted on shaft 10 which is driven from any suitable source of power. Pulley 9 is also provided with a wheel 11, to which is eccentrically connected at 12, the rod 13, whereby said rod 13 is adapted to be reciprocated in front of the aperture 14 of casing 4. To rod 13 is also pivoted at 15, one end of the rocking lever 16, supported at 17 by the arm 18. The other end of lever 16 is pivotally connected at 19 with rod 20, which is adapted to reciprocate, through opening 21, across the path of travel of the coils 22, in the chute 5. The relative diameters of the pulley not shown on shaft 7 and the pulley 9, which are

connected by chain 8, are such as to secure one complete rotation of shaft 7 with six rotations of wheel 11. By this construction it will be seen that when rod 13 is withdrawn, from the path of travel of the coils 22 in chute 5 a coil is permitted to slide into one of the compartments between the partitions 6. At the same time that rod 13 is so withdrawn, rod 20 has been moved upwardly across the path of travel of the coils 22, so that only one coil will be permitted to enter a compartment. As the partitions move forwardly in the direction of the arrow shown in Fig. 1, a new compartment is presented to aperture 14 while, at the same time members 13 and 20 have so shifted as to permit the movement of another coil downwardly against member 13, while with a still further movement of the rotating structure the positions of 13 and 20 are again reversed to repeat the operation above described. That is to say each compartment during its passage past aperture 14 of casing 4 receives one coil. It is of course obvious that the proportions and dimensions may be so varied as to permit the delivery of any desired number of coils to each compartment.

The compartments indicated by *a*, *b* and *c* will serve to show three positions in the operation of the delivery mechanism; *a* shows the position of a compartment after it has received a coil from the chute. When one partition 6 has moved past the aperture 14 of the casing 4, the partition just in advance has passed the pipe 23, so that steam, gas or other non-oxidizing agent is admitted into the compartment between said two partitions and the oxidizing atmosphere contained in said compartment is expelled through air pipe 24. When the partitions bounding the compartment reaches the position indicated by *b* in Fig. 1, the non-oxidizing agent is still entering the compartment and the oxidizing atmosphere is being expelled through air pipe 25, so that when the compartment reaches the position indicated by *c*, it is quite free of oxidizing atmosphere and is now communicating with the aperture 26 of retort 1, so that the coil 22 may be delivered into the retort, and onto the conveyer 37. The coils delivered onto the conveyer 37 are carried forward to the retort in the direction of the arrow and discharged through the inclined extension 2 into the water tank 3, where the coils are cooled before coming into contact

with the oxidizing atmosphere. The retort 1 may be freed from oxidizing atmosphere in the usual way by the introduction of steam, gas or other non-oxidizing agent through pipe 28 and expulsion of air through pipe 29. The coils may be discharged in the water tank upon the conveyer 27 and thereby carried upwardly out of said tank.

A substantially air-tight movable joint is provided between the rotating structures forming the compartments and the stationary casing surrounding the same, by the following devices; in the slotted end of each partition 6 is provided the plate 30, actuated by the bow spring 31 to cause the outer edge of said plate to press efficiently against the inner circumference of the stationary casing 4. In the sides of the stationary casing 4 are provided the annular channels 33 in which are seated the packing rings 32 actuated by a series of bow springs 34 to cause said rings to press efficiently against the sides 35 of the rotating structure and also against the ends of members 30. It is needless to say that the inner peripheral surface of the stationary casing 4, and the coöperating or contacting surface of member 30, and the coöperating surfaces of 35 and 32 are machined, or otherwise made sufficiently smooth and true, to fit and 30 maintain an efficient movable seal for the purposes indicated.

One of the advantages of introducing the coils of wire into the retort without passing the same through a liquid seal, is that an economy of fuel is secured in maintaining the retort at the required temperature. It is also advantageous to locate the conveyer 37 entirely within the retort, and without having it pass through a liquid seal, since by this arrangement a saving of fuel is secured, and also the damage to the conveyer, consequent upon the alternate heating and cooling thereof, is prevented.

My device is especially useful in the annealing of metals which it is not desirable to pass through a liquid seal before entering the retort.

What I claim is:—

1. In combination with a retort, a movable body provided with a chamber movable to a position open to the atmosphere, then to a position closed to atmosphere and retort, and then to a position open to the retort, and means for expelling oxidizing atmosphere from the chamber while in said closed position.

2. In combination with a retort, a rotatable body provided with a charging chamber movable to a position open to the atmosphere, then to a position closed to atmosphere and retort, and then to a position open to the retort, and means for expelling oxidizing atmosphere from the chamber while in said closed position.

3. In combination with a retort, a fixed

casing inclosing the receiving aperture of the retort, a rotatable body inclosed in said casing, provided with a chamber movable, from a position in which the chamber is open to the outside atmosphere, to a position closed from the outside atmosphere, and the retort, and then to a position open to the retort, and means for expelling oxidizing atmosphere from the chamber while in the said closed position.

4. In combination with a retort, a fixed casing inclosing the receiving aperture of the retort, a rotatable body inclosed in said casing, provided with a chamber movable, from a position in which the chamber is open to the outside atmosphere, to a position closed from the outside atmosphere and the retort, and then to a position open to the retort, means for expelling oxidizing atmosphere from the chamber while in the said closed position, and automatic means operated relatively to the rotatable body for controlling the delivery of stock to the movable chamber.

5. In combination with a retort, a fixed casing inclosing the receiving aperture of the retort, a rotatable body inclosed in said casing, provided with a chamber movable, from a position in which the chamber is open to the outside atmosphere, to a position closed from the outside atmosphere and the retort, and then to a position open to the retort, means for expelling oxidizing atmosphere from the chamber while in the said closed position, and means for maintaining a movable seal between the rotatable body and the fixed casing.

6. In combination with a retort, a fixed casing inclosing the receiving aperture thereof, a rotatable body inclosed in said casing, provided with a plurality of chambers movable, one after the other, from a position in which each in turn is open to the outside atmosphere, then to a position closed to the outside atmosphere and the retort, and then to a position open to the retort, and means for expelling oxidizing atmosphere from each chamber when in said closed position, the said chambers being so proportioned and positioned with respect to the inclosing casing, that one chamber will be receiving material, while oxidizing atmosphere is being expelled from another, and while another chamber is delivering to the retort.

7. In combination with a retort, a fixed casing inclosing the receiving aperture thereof, a rotatable body inclosed in said casing, provided with a plurality of chambers movable, one after the other, from a position in which each in turn is open to the outside atmosphere, then to a position closed to the outside atmosphere and the retort, and then to a position open to the retort, means for expelling oxidizing atmosphere from each chamber when in said closed position, the said cham-

bers being so proportioned and positioned with respect to the inclosing casing that one chamber will be receiving material, while oxidizing atmosphere is being expelled from another, and while another chamber is delivering to the retort, and automatic means, operated relatively to the operation of the

rotating body, for delivering the required quantity of stock to each chamber passing a given point.
